UNITED STATES PATENT OFFICE.

CORNELIUS KEVITT, OF GLEN RIDGE, NEW JERSEY, ASSIGNOR OF TWO-THIRDS TO
A. W. SIMPSON, OF UPPER MONTCLAIR, NEW JERSEY.

TRANSOM-OPERATING MEANS.

1,159,951.

Specification of Letters Patent.

Patented Nov. 9, 1915.

Application filed May 8, 1915. Serial No. 26,754.

To all whom it may concern:

Be it known that I, CORNELIUS KEVITT, a citizen of the United States, residing at Glen Ridge, in the county of Essex and State of New Jersey, have invented certain new and useful Improvements in Transom-Operating Means, of which the following is a specification.

This invention relates to transom operating means and has for its primary object to provide simple and efficient mechanism which is adapted to be installed entirely within a hollow-column forming one of the door posts of the doorway to a room.

One of the objects of the present invention is to provide an improved device of this character which is rapid in its action, economical to manufacture, and which requires small effort to manipulate.

With these and other objects in view my invention consists in the combination and arrangement of parts of simple construction referred to in the specification in connection with the accompanying drawings, in which,

Figure 1 is a front elevation of a door and door frame provided with my improved transom operating mechanism. Fig. 2 is a section of the door jamb or door frame column showing the main parts of said mechanism in side elevation; Fig. 3 is a similar view with the front wall of said column removed showing the parts in positions corresponding to the transom in open position; Fig. 4 is a front elevation of Fig. 2; Fig. 5 is a fragmentary detail section; Figs. 6, 7, 8 and 9 are detail perspective views to be hereinafter referred to. Fig. 10 is a detail section of one branch of either of the corner brackets shown in Figs. 6 and 9.

It is well known in the art to provide transom operating mechanism which is contained almost entirely within the door jamb or a hollow column in which one end of the transom is journaled. Various mechanical trains have been employed of which some occupied small space but required considerable time and effort to manipulate, and often-times expensive to manufacture.

The advantageous features of the present invention will be seen from the following description of the preferred embodiment of my invention shown on the drawing.

The door frame shown in Fig. 1 includes the laterally spaced hollow columns 1 and 2 on opposite sides of the closed door 3, a

transom 4 being swingingly mounted above the door and provided with operating connections presently to be referred to, in the hollow jamb or column 2, a knob 5 being mounted on the outer end of a hand lever 6 which is shown in Figs. 2 and 3, is pivoted at 7 on a pad or block 8, on an inner wall of the hollow column. A stop or lug 9 on said pad or block retains the lever 6 in either position to which it is moved, a yieldable strap 10 being adapted to permit a swinging movement of said lever but tending to hold it behind the shoulder at either end of said lug. The lower end of a connecting rod 11 is connected at 12 with lever 6, its upper end being connected at 13 to the horizontal arm 14 of a bell crank pivoted at 15. The upwardly extending arm 16 of said bell crank is provided with a slot 17 for slidably accommodating a stud 18 on the lower end of a lever 19 which is pivoted at 20 adjacent the free edge of said transom 4 in closed position as shown in Fig. 2. The lever 19 is provided with a slot 21 intermediate of its ends, within which slides a stud 22 carried by a crank arm 23 which as shown in Fig. 5 is provided with an integrally formed cylinder 24 journaled in a wall of the hollow jamb or column 2. Secured to the lower right hand corner of the transom 4 is a corner bracket 25 which is rounded below as shown in Figs. 6 and 10. Projecting from said corner bracket is a squared lug 26 which fits a correspondingly formed socket in the portion 24 of crank arm 23. A cotter 27 prevents the separation of crank arm 23 and corner bracket 25. A packing plate 28 provided with a hole 29 to accommodate portion 24, is interposed between crank arm 23 and the wall of said hollow column 2. The corner bracket 30 shown in Fig. 9 is secured to the lower left hand corner of the transom 4 and provided with a pintle 31 which is coaxial with the journal 24 and adapted to be positioned in a fixed plate 32 carried by the door jamb 1 through a slot 23. The advantages of this construction will now be readily understood in connection with the foregoing description. Thus by arranging the lever 19 to swing about an axis adjacent the path of the swinging edge of the transom, it becomes possible to secure a relatively long power arm with respect to a work arm which is included in the power arm and all contained

within the confines of a hollow door jamb. At the same time, by the employment of the connecting rod 11, it is possible to provide a bell crank 16 which is sufficiently small to be contained in the hollow door jamb while at the same time providing ample angular movement for the lever 19. A further multiplication of the power is provided by the hand lever 6. It is to be noted that all of 10 the connections are simple, pivotal bearings which transmit power in a direction substantially tangential to the pivoted elements and lengthwise of the connecting rod 11 in such a way as to enable the transom 4 to be 15 operated by mechanism contained wholly within the hollow jamb 2 and with the least possible effort applied to hand lever 6 consistent with rapid manipulation.

One of the great advantages of the foregoing construction is that it may be inclosed in a hollow column 1" x 4" for its complete operation. It requires only a movement of $2\frac{1}{2}$ " to either open or close the transom to full capacity and gives sufficient leverage for 25 easily opening and closing heavy transoms which are quite difficult to move by present well known devices.

What I claim is:

1. In a device of the character described, 30 a hollow column, a frame or transom without said hollow column, said frame or transom being movable about an axis, a lever mounted within said hollow column on a fixed pivot above said axis and extending 35 below said axis, means extending through the wall of said hollow column for transmitting the movement of said lever to said frame or transom, an operating member extending from within said hollow column, 40 and means for connecting said operating member to said lever.

2. In a device of the character described, 45 a hollow column, a frame or transom journaled at one end in the wall of said hollow column, a crank arm carried by said frame or transom, a lever mounted within said hollow column on a fixed pivot above the journaling axis of said frame or transom, said lever depending from said pivot and having 50 an operating connection with said crank arm, an operating member extending through the wall of said hollow column below said lever, and means within said hollow column 55 for connecting a portion of said lever below said crank arm to said operating member.

3. In a device of the character described, 60 a pivotally mounted frame or transom, a lever pivoted at one end and having means intermediate its ends for moving said frame or transom, a lever arm movable about an axis below the first mentioned lever, and means for connecting the other end of the first mentioned lever to the second mentioned lever.

4. In a device of the character described,

the combination with a frame movable about an axis, of a lever pivoted at one end and provided with means intermediate of its ends for moving said frame on its axis, and means connected to the other end of said lever for swinging it on its pivot, said swinging means including a bell crank lever having one arm connected to the first mentioned lever, and means for oscillating the other arm of said bell crank lever. 70

5. In a device of the character described, the combination with a frame movable about an axis, of a lever pivoted at one end and provided with means intermediate of its ends for moving said frame on its axis, and means connected to the other end of said lever for swinging it on its pivot, said swinging means including a bell crank lever having one arm pivotally connected to the first 80 said lever, a reciprocable bar connected to the other arm of said bell crank lever, and means for reciprocating said bar. 85

6. In a device of the character described, a hollow column, a frame oscillatable about an axis, a lever within said hollow column and having one end mounted to swing about an axis, a bell crank lever within said column and having one arm connected to said lever, means journaled in the wall of said hollow column and operatively connecting 90 said frame to said lever intermediate to the pivot of said lever and its point of connection with said bell crank lever and a rod reciprocable lengthwise of said column connected to the other arm of said bell crank 100 lever. 95

7. In a device of the character described, a hollow column, a frame oscillatable about an axis, a lever within said hollow column and having one end mounted to swing about an axis, a bell crank lever within said column and having one arm connected to said lever, means journaled in the wall of said hollow column and operatively connecting 105 said frame to said lever intermediate to the pivot of said lever and its point of connection with said bell crank lever and a rod reciprocable lengthwise of said column connected to the other arm of said bell crank 110 lever, said frame and lever connecting means including a crank arm slidably engaging said lever and provided with an integral cylinder journaled in the wall of said column, and a projection carried by said frame and non-rotatably engaging said cylinder. 115

8. In a device of the character described, a hollow column, a lever pivotally suspended within said hollow column, a swinging frame or transom having means journaled in the wall of said column for connecting 125 said frame to said lever intermediate to the ends of said lever; a bell crank pivoted below said lever within said column and having an upwardly extending arm connected to the depending end of the first said 130

- lever, and means connected to the other arm of said bell crank for oscillating said lever and frame or transom.
9. In a device of the character described, 5 a hollow column, a lever pivotally suspended within said hollow column, a swinging frame or transom having means journaled in the wall of said column for connecting said frame to said lever intermediate to the ends of said lever, a bell crank pivoted below said lever within said column and having an upwardly extending arm connected to the depending end of the first said lever, and means connected to the other arm of said bell 10 crank for oscillating said levers and frame or transom, the pivotal axis of said bell crank being arranged in the same vertical plane with the axis of suspension of the first mentioned lever, said oscillating means 15 including a rod extending substantially parallel to the plane of said axis.
10. In a device of the character described, 20 a hollow column, a lever pivotally suspended within said hollow column, a swinging frame or transom having means journaled in the wall of said column for connecting said frame to said lever intermediate to the ends of said lever, a bell crank pivoted below said lever within said column and having an upwardly extending arm connected to the depending end of the first said lever, and means connected to the other arm of said bell 25 crank for oscillating said lever and frame or transom, said oscillating means including a rod extending lengthwise of said column and having its upper end connected to the other arm of said bell crank, and a hand operated lever pivoted at one end within said column and connected to the lower end of said rod within said column.
11. In a device of the character described, 30 a hollow column, a lever pivotally suspended within said hollow column, a swinging frame or transom having means journaled in the wall of said column for connecting said frame to said lever intermediate to the ends of said lever, a bell crank pivoted below said lever within said column and having an upwardly extending arm connected to the depending end of the first said lever, and means connected to the other arm of said bell 35 crank for oscillating said lever and frame or transom, the pivotal axis of said bell crank being arranged in the same vertical plane with the axis of suspension of the first mentioned lever, said oscillating means including a rod extending substantially parallel to the plane of said axis.
12. In a device of the character described, 40 a hollow column, a lever pivotally suspended within said hollow column, a swinging frame or transom having means journaled in the wall of said column for connecting said frame to said lever intermediate to the ends of said lever, a bell crank pivoted below said lever within said column and having an upwardly extending arm connected to the depending end of the first said lever, and means connected to the other arm of said bell 45 crank for oscillating said lever and frame or transom, said oscillating means including a rod extending lengthwise of said column and having its upper end connected to the other arm of said bell crank, and a hand operated lever pivoted at one end within said column and connected to the lower end of said rod within said column.

CORNELIUS KEVITT.
